UNITED STATES PATENT OFFICE.

JOSEPH B. STRAUSS. OF CHICAGO, ILLINOIS.

BRIDGE.

1,171,553.

Specification of Letters Patent.

Patented Feb. 15, 1916.

Application filed April 1, 1913. Serial No. 758,140.

To all whom it may concern:

Be it known that I, JOSEPH B. STRAUSS, a citizen of the United States, residing at Chicago, in the county of Cook and State of Illinois, have invented a certain new and useful Improvement in Bridges, of which the following is a specification.

This invention relates to bridges and has for its object to provide a new and improved bridge of the bascule type.

The invention is illustrated in the accompanying drawings wherein—

Fig. 1 is a view showing one form of bridge embodying the invention; Fig. 2 is a plan view of the device shown in Fig. 1; Fig. 3 is a view showing a modified construction; Fig. 4 is a perspective view showing a portion of the counterweight; Fig. 5 is a view showing the method of reinforcing the counterweight.

Like numerals refer to like parts throughout the several figures.

Referring now to Figs. 1 and 2 of the drawings, I have shown a movable span 1 pivotally mounted at 2 upon the supports 3. A counterweight frame or support 4 is connected with the movable span and is provided with a counterweight 5. The counterweight frame or support 4 has a plurality of angularly disposed members, said members having an angular open space between them, the open end of the space being at the bottom thereof. As shown in Fig. 1, the counterweight frame has connecting members 6 and 7 extending upwardly from the counterweight and the support for the counterweight frame, said members being connected at a point above the plane passing through the lower ends thereof, the connection being shown at the point 8. This connection allows the movable span to be moved to its open position without the counterweight frame coming in contact with any of the stationary parts. In the construction shown in Figs. 1 and 2, the trunnions of the movable span 1 have inside bearings 9 and outside bearings 10 (see Fig. 2). There is an inside post or support for each inside bearing and a brace 11 between each of said posts and the fixed portion 12 so as to take the horizontal thrust on said inside bearings. This fixed support 12 is shown as a girder extending across between the stationary pieces 13 of the fixed portion of the bridge. The braces 11 form knee braces between the

supports for the bearings and the stationary piece or girder 12.

Figs. 3, 4 and 5 show a construction where in the counterweight 5 is provided with a series of angular members 14 embedded in the concrete and connected with the counterweight support. These angular members 14 are preferably arranged to form triangular trusses. There are also a series of interconnecting members 15 between the triangular trusses, the triangular trusses and interconnecting members being embedded in the concrete. The counterweight is provided with a bottom portion 16 and side portions 17. The side portions 17 are preferably supported upon the angular members or trusses of the counterweight in any desired manner and the concrete is then applied, said bottom and side portions acting as a self-supporting frame for the counterweight while the concrete is being erected, thereby making it unnecessary to have false work for this purpose.

It will be seen that there is here provided a bridge having a counterweight frame connected therewith and a rigid counterweight fixed to said counterweight frame and depending therefrom when the bridge is closed.

As illustrated, the pieces 17 and 16 are suspended on the counterweight truss by means of bolts 18. Some suitable operating mechanism is provided for moving the main span about its pivots, such as for example, the rack 19 and the pinion 20. The counterweight is located below the roadway 21.

By means of this construction where the tail end of the main span has the reentrant angle, that is the construction where there is an angular open space between the members into which the cross fixed support may enter as the bridge is lifted, provides an efficient means for using this cross support and still getting the full opening of the bridge and a construction in which the cost is very materially reduced. The construction of the counterweight, also, reduces the cost, as the particular manner in which the metal is disposed is much more economical and permits the use of a concrete counterweight greatly reduced in cost and yet efficiently supported and of the proper strength and durability. This construction was particularly provided to avoid difficulties found in attempting to adapt in actual practice the large concrete counterweights necessary for

large bridges and which have to be changed in position so as to change the strains as the bridge is opened and closed.

I claim:

- 5 1. A bascule bridge comprising a movable span, a counterweight frame associated with said movable span upon which the counterweight is supported, said counterweight frame having a plurality of angularly disposed members, said members having an angular open space between them, the open end of said space being at the bottom thereof, a cross support extending under said movable span, inside and outside bearings 10 for said movable span, mounted upon said cross support, said cross support received in said space between said angularly disposed members when the movable span is moved to its open position.
- 15 2. A bridge comprising a main span, a counterweight support connected therewith, a series of angular members connected together to form a plurality of triangles, said angular members connected with said counterweight support, concrete connected with said angular members and in which they are embedded.
- 20 3. A bascule bridge comprising a fixed portion, a movable portion mounted on trunnions, an inside and outside bearing for the trunnions, an inside support for the inside bearing and a brace between said support and said fixed portion so as to take the horizontal thrust of said inside bearing.
- 25 4. A bascule bridge comprising a main span provided with a plurality of trusses, a fixed support, a portion of which extends underneath the main span, a counterweight carrying part comprising a member behind the support and extending upwardly therefrom, a second member extending upwardly from said first member at a distance from its point of connection with the span, said second member also connected with said 30 span, a third member projecting rearwardly from the upper chord of the main span, the
- 35 three members forming a supporting frame, a series of triangular members connected with said frame, a counterweight connected with said triangular members, there being 50 an open space between said first member and said series of triangular members so that said members clear the support in all of the various positions of the main span.
- 40 5. A bascule bridge comprising a main span, trunnions upon which it is mounted, said main span terminating at said trunnions, a triangular frame built out from said span toward the rear thereof, a series of triangular frames carried upon said first 55 mentioned triangular frame as a support, a counterweight carried by said series of triangular frames, said series of triangular frames separated from the first triangular frame by a space open at the bottom, a cross 60 support under said main span, said cross support received into said space when the main span is open.
6. A bridge comprising a main span, a counterweight therefor comprising a series of 70 triangular trusses connected with said main span, a series of interconnecting members between said triangular trusses, said trusses and members embedded in concrete.
7. A bascule bridge comprising a main 75 span, trusses therefor, a concrete counterweight therefor comprising a metal bottom portion, two metal side portions associated with the bottom portion, trusses between said side portions and connected to the trusses 80 associated with the main span, said side portions supported on said trusses, the bottom and side portions constituting a self-supporting form for concrete while the counterweight is being erected.

In testimony whereof, I affix my signature in the presence of two witnesses this 31st day of March, 1913.

JOSEPH B. STRAUSS.
